(57) **CLAIM**

The ornamental design for cassette assembly for electrophoresis gel, as shown and described.

DESCRIPTION

FIG. 1 is an exploded front perspective of a cassette assembly for electrophoresis gel

FIG. 2 is a front perspective view of the assembled cassette assembly for electrophoresis gel, of FIG. 1;

FIG. 3 is a back perspective view of the cassette assembly for electrophoresis gel, of FIG. 2;

FIG. 4 is a front view of the cassette assembly for electrophoresis gel, of FIG. 2;

FIG. 5 is a back view of the cassette assembly for electrophoresis gel, of FIG. 2;

FIG. 6 is a right side view of the cassette assembly for electrophoresis gel, of FIG. 2;

FIG. 7 is a left side view of the cassette assembly for electrophoresis gel, of FIG. 2;

FIG. 8 is a top view of the cassette assembly for electrophoresis gel, of FIG. 2;

FIG. 9 is a bottom view of the cassette assembly for electrophoresis gel, of FIG. 2;

FIG. 10 is an exploded front perspective view of the top and bottom plates of the cassette assembly for electrophoresis gel, of FIG. 1;

FIG. 11 is a front perspective view of the top and bottom plates of the assembled cassette assembly for electrophoresis gel, of FIG. 10;

FIG. 12 is a back perspective view of the top and bottom plates of the cassette assembly for electrophoresis gel, of FIG. 11;

FIG. 13 is a front view of the top and bottom plates of the cassette assembly for electrophoresis gel, of FIG. 11;

FIG. 14 is a back view of the top and bottom plates of the cassette assembly for electrophoresis gel, of FIG. 11;

FIG. 15 is a right side view of the top and bottom plates of the cassette assembly for electrophoresis gel, of FIG. 11;

FIG. 16 is a left side view of the top and bottom plates of the cassette assembly for electrophoresis gel, of FIG. 11;

FIG. 17 is a top view of the top and bottom plates of the cassette assembly for electrophoresis gel, of FIG. 11;

FIG. 18 is a bottom view of the top and bottom plates of the cassette assembly for electrophoresis gel, of FIG. 11;

FIG. 19 is an exploded front perspective view of the top plate and comb of the cassette assembly for electrophoresis gel, of FIG. 1;

FIG. 20 is a front perspective view of the top plate and comb of the assembled cassette assembly for electrophoresis gel, of FIG. 19;

(Continued)

FIG. 21 is a back perspective view of the top plate and comb of the cassette assembly for electrophoresis gel, of FIG. 20; FIG. 22 is a front view of the top plate and comb of the cassette assembly for electrophoresis gel, of FIG. 20; FIG. 23 is a back view of the top plate and comb of the cassette assembly for electrophoresis gel, of FIG. 20; FIG. 24 is a right side view of the top plate and comb of the cassette assembly for electrophoresis gel, of FIG. 20; FIG. 25 is a left side view of the top plate and comb of the cassette assembly for electrophoresis gel, of FIG. 20; FIG. 26 is a top view of the top plate and comb of the cassette assembly for electrophoresis gel, of FIG. 20; FIG. 27 is a bottom view of the top plate and comb of the cassette assembly for electrophoresis gel, of FIG. 20; FIG. 28 is a front perspective view of the comb of the cassette assembly for electrophoresis gel, of FIG. 1; FIG. 29 is a back perspective view of the comb of the cassette assembly for electrophoresis gel, of FIG. 28; FIG. 30 is a front view of the comb of the cassette assembly for electrophoresis gel, of FIG. 28; FIG. 31 is a back view of the comb of the cassette assembly for electrophoresis gel, of FIG. 28; FIG. 32 is a right side view of the comb of the cassette assembly for electrophoresis gel, of FIG. 28; FIG. 33 is a left side view of the comb of the cassette assembly for electrophoresis gel, of FIG. 28; FIG. 34 is a top view of the comb of the cassette assembly for electrophoresis gel, of FIG. 28; FIG. 35 is a bottom view of the comb of the cassette assembly for electrophoresis gel, of FIG. 28; FIG. 36 is a front perspective view of the top plate of the cassette assembly for electrophoresis gel, of FIG. 1; FIG. 37 is a back perspective view of the top plate of the cassette assembly for electrophoresis gel, of FIG. 36; FIG. 38 is a front view of the top plate of the cassette assembly for electrophoresis gel, of FIG. 36; FIG. 39 is a back view of the top plate of the cassette assembly for electrophoresis gel, of FIG. 36; FIG. 40 is a right side view of the top plate of the cassette assembly for electrophoresis gel, of FIG. 36; FIG. 41 is a left side view of the top plate of the cassette assembly for electrophoresis gel, of FIG. 36; FIG. 42 is a top view of the top plate of the cassette assembly for electrophoresis gel, of FIG. 36; FIG. 43 is a bottom view of the top plate of the cassette assembly for electrophoresis gel, of FIG. 36;

FIG. 44 is a front perspective view of the bottom plate of the cassette assembly for electrophoresis gel, of FIG. 1; FIG. 45 is a back perspective view of the bottom plate of the cassette assembly for electrophoresis gel, of FIG. 44; FIG. 46 is a front view of the bottom plate of the cassette assembly for electrophoresis gel, of FIG. 44; FIG. 47 is a back view of the bottom plate of the cassette assembly for electrophoresis gel, of FIG. 44; FIG. 48 is a right side view of the bottom plate of the cassette assembly for electrophoresis gel, of FIG. 44; FIG. 49 is a left side view of the bottom plate of the cassette assembly for electrophoresis gel, of FIG. 44; FIG. 50 is a top view of the bottom plate of the cassette assembly for electrophoresis gel, of FIG. 44; and, FIG. 51 is a bottom view of the bottom plate of the cassette assembly for electrophoresis gel, of FIG. 44.
